CLAIM

I claim the ornamental design for the combined folding door jamb, end panel and mini slats, as shown and described.

DESCRIPTION

FIG. 1 is a front elevational view of the combined folding door jamb, end panel and mini slats without surface ornamentation. The oval circle in FIG. 1 referencing a detail of the front of the folding door in FIG. 2. The rear view of the folding door shown in FIG. 1 being a mirror image of the front view.

FIG. 2 is an enlarged front view of the combined folding door jamb, end panel and mini slats taken from the upper portion in FIG. 1.

FIG. 3 is a bottom view of the folding door without surface ornamentation shown in FIG. 1.

FIG. 4 is a top view of the folding door without surface ornamentation shown in FIG. 1.

FIG. 5 is a left side view of the folding door without surface ornamentation shown in FIG. 1.

FIG. 6 is a right side view of the folding door without surface ornamentation shown in FIG. 1.

FIG. 7 is a front elevational view of the folding door jamb, end panel and mini slats with wood grain surface ornamentation. The oval circle in FIG. 7 referencing a detail of the front of the folding door in FIG. 8. The rear view of the folding door shown in FIG. 7 being a mirror image of the front view.

FIG. 8 is an enlarged front view of the combined folding door jamb, end panel and mini slats taken from the upper portion in FIG. 7.

FIG. 9 is a bottom view of the folding door with surface ornamentation shown in FIG. 7.

FIG. 10 is a top view of the folding door with surface ornamentation shown in FIG. 7.

FIG. 11 is a left side view of the folding door with surface ornamentation shown in FIG. 7; and,

FIG. 12 is a right side view of the folding door with surface ornamentation shown in FIG. 7.

The broken lines showing castors and mini slats are for illustrative purposes only and are not part of the claim design.

The broken away sections illustrate indefinite length of the claimed design.
